US00D820865S

(12) **United States Design Patent** (10) Patent No.: **US D820,865 S**
Muhsin et al. (45) Date of Patent: **** Jun. 19, 2018**

(54) **DISPLAY SCREEN OR PORTION THEREOF FOR GRAPHICAL USER INTERFACE FOR PHYSIOLOGICAL MONITORING**

(71) Applicant: **MASIMO CORPORATION**, Irvine, CA (US)

(72) Inventors: **Bilal Muhsin**, Aliso Viejo, CA (US); **Sujin Hwang**, Rancho Santa Margarita, CA (US); **Benjamin C. Triman**, Rancho Santa Margarita, CA (US)

(73) Assignee: **Masimo Corporation**, Irvine, CA (US)

(**) Term: **15 Years**

(21) Appl. No.: **29/579,574**

(22) Filed: **Sep. 30, 2016**

CLAIM

The ornamental design for a display screen or portion thereof with a graphical user interface for physiological monitoring, as shown and described.

DESCRIPTION

The sole FIGURE is the front view of a display screen or portion thereof with a graphical user interface for physiological monitoring.

The dashed broken lines in the drawings depict environmental structure that forms no part of the claimed design, and the dash-dot-dash broken line perimeter surrounding the display screen or portion thereof in the drawings indicates the boundaries of the claim and forms no part thereof.
